MARK E. CHIVVIS, OF MANTON, MICHIGAN.

VALVE-PORT PACKING.

1,215,484.

Specification of Letters Patent. Patented Feb. 13, 1917.

Application filed March 24, 1916. Serial No. 86,339.

To all whom it may concern:

Be it known that I, MARK E. CHIVVIS, a citizen of the United States, residing at Manton, in the county of Wexford, State 5 of Michigan, have invented a new and useful Valve-Port Packing, of which the following is a specification.

This invention relates to packing means for the valve ports of internal combustion 10 engines, and consists in the novel features of construction and arrangement of parts as hereinafter set forth and claimed.

The invention has for its object the provision of simple and efficient means for 15 packing the joints surrounding the valve ports of internal explosive engines, and especially in that type of engine employing rotary or sliding sleeve valves in which the ports are controlled by direct surface contact of the moving valve, so as to secure and constantly maintain a close working 20 yieldable contact between the engaged parts in a manner to insure a gas-tight seal of the joints and prevent the escape of pressure 25 and the consequent loss of power in the engine.

In attaining the above object the invention contemplates the employment of a rectangular frame composed of right-angled 30 adjoining triangular corner pieces having their angular extensions overlapping each other diagonally upon opposite ends and sides to render the frame expansible longitudinally and transversely through the sliding contact afforded between the frame members. This frame is freely seated in a 35 channel or recess formed in the outer face surrounding the port of the valve case and is yieldably held in surface contact with the inner face of the valve controlling the port by means of a rectangular leaf-spring which 40 is seated in the recess to flexibly bear against the inner face of the frame and yieldably force it into engagement with said valve so 45 as to form a close working joint and tight seal around said port.

A preferred embodiment of the essential features of the present invention is illustrated in the accompanying drawings, in 50 which,

Figure 1 is a sectional view of the head portion of an engine cylinder showing the

packing in position surrounding the port of the valve case.

Fig. 2 is a front elevation of a portion of 55 the valve case with packing in position around the port.

Fig. 3 is a fragmentary horizontal section through the valve port and packing, taken on dotted line 3-3 of Fig. 1.

Fig. 4 is a transverse section through the valve port, valve and packing, taken on dotted line 4-4 of Fig. 2.

Fig. 5 is an elevation of a rectangular sheet metal spring for exerting pressure on 65 the packing frame.

Fig. 6 is a perspective view of two of the corner sections of the packing frame withdrawn from each other to show the tongue and groove joint connections.

Referring to the parts by the characters of reference marked on the drawings, 1 indicates the head-end portion of an engine cylinder within which is mounted a fixed sleeve or valve case 2 having a port 3 therein, and concentrically interposed between 75 said valve case and the inner wall of the engine cylinder is a rotatable sleeve valve 4 having a port 5 adapted to register with the port of said valve case, as is common in rotary valve engines.

Formed in the outer face of the valve case 2 surrounding the port 3 therein, which is preferably rectangular in form, is a rectangular recess or channel 6 lying adjacent 85 to and embracing the marginal edges 7 of said port. The bottom wall of this channel is formed arcuate to conform with the arc of the valve case, and seated to bear at its ends and inner edges upon the arcuate 90 bottom and fitting freely within the side walls of said channel is a flat sheet metal spring frame 8 which bears at opposite ends upon the vertex of the arcuate channel over which the side portions of said spring will 95 be free to flex when subjected to pressure. (See Fig. 4).

Fitting freely within the channel 6 and bearing at the outer edges of its inner face upon the outer edges at opposite sides of 100 the outer face of the spring 8 is a packing frame which is composed of a series of right-angled corner pieces 9 having their angular extensions 10 acutely tapered and

assembled in reversely opposed diagonally overlapping relation with each other upon opposite sides and ends of the frame formed thereby. (See Fig. 2). The overlapping 5 engaged edges of the angular extensions of the corner pieces are provided with interengaging tongues and grooves 11 and 12 respectively, which serve to retain the members against lateral displacement upon each 10 other and effect a close fitting slidable joint connection between the sections to permit the frame to move laterally as a whole within the channel and to render it flexible and expansibly adjustable longitudinally and 15 transversely therein.

The surface formation of the frame sections is such as to conform the inner face of the frame to the arc of the channel of the valve case and the outer face to the inner 20 arc of the valve sleeve 4 against which said frame is yieldably forced by the flexing tension exerted by the leaf-spring upon opposite sides thereof. (See Figs. 3 and 4).

It will be apparent from the foregoing 25 that by this arrangement of parts a flexible and serviceable packing is formed around the valve port which will insure the maintenance of a close, yet free working joint between the valve case and valve to prevent 30 the gases when passing through the port under pressure from escaping between the valve case and valve.

Having thus fully set forth my invention,

I claim as new and desire to secure by Letters Patent, the following:

1. In combination with a ported valve case having a channel in the face thereof adjacent to and surrounding the port therein and a valve embracing said valve case for controlling said port, an expansible packing member composed of a series of adjoining diagonally overlapping sections slidably interengaged and movably seated as a whole within said channel, and a flexible member seated in said channel and bearing against 45 said packing member to retain it yieldably engaged with said valve.

2. In combination with a ported valve case having a channel in the face thereof surrounding the port therein and a valve embracing said case for controlling said port, an expansible packing member composed of a plurality of right-angled sections having diagonally overlapping tapering extensions provided with interengaging tongues and 55 grooves slidably joining and retaining said sections against lateral displacement, the whole being movably seated within said channel, and a leaf-spring flexibly seated in said channel and bearing against said packing member to yieldably retain said member in contact with said valve.

In testimony whereof, I sign this specification.

MARK E. CHIVVIS.
